(57) **CLAIM**

I claim the ornamental design for a bed table, as shown and described.

DESCRIPTION

FIG. 1 is a perspective view of a bed table showing my new design;

FIG. 2 is a side elevational view thereof;

FIG. 3 is an end elevational view thereof;

FIG. 4 is an elevational view of the opposing side thereof;

FIG. 5 is a top plan view thereof;

FIG. 6 is a bottom plan view thereof;

FIG. 7 is an elevational view of the opposing end thereof; and,

FIG. 8 is a perspective view showing the bed table in use; the broken lines depict environmental structure for illustrative purposes only and form no part of the claimed design.

The cord member shown in FIGS. 1, 2, 3, 4, and 7 is shown broken away and in fragment for ease of illustration.
